United States Patent Office

Des. 206,463
Patented Dec. 13, 1966

206,463

BOTTLE

George J. Federighi, Belvedere, Calif. (% Stero Chemical Mfg. Co., 70 13th St., San Francisco, Calif. 94103)

Filed Oct. 18, 1965, Ser. No. 87,539

Term of patent 14 years

(Cl. D58—8)

FIG. 1.

FIG. 2.

FIG. 1 is a top plan view of a bottle showing my new design; and

FIG. 2 is a side elevational view thereof.

The bottle is symmetrical about its vertical axis, and all elevational views thereof are identical with that shown in FIG. 2.

I claim:

The ornamental design for a bottle, substantially as shown and described.
